UNITED STATES PATENT OFFICE.

CHARLES D. McARTHUR, OF PITTSBURGH, PENNSYLVANIA.

CONCRETE WALL CONSTRUCTION.

Application filed August 30, 1926. Serial No. 132,342.

The invention relates to concrete wall constructions of the built-up block form. It has for its principal objects, the provision of an improved construction of cheap, simple design, which can be used in a wide variety of forms, so that the blocks may be used to duplicate in appearance all the parts of a stone or brick building, and the provision of a construction having an unusual degree of strength and security at the meeting edges of the blocks, and one in which the fastening means are easily applied. Other objects and advantages incident to the construction will be readily apparent to those skilled in the art from a consideration of the specification following and of the drawings, wherein:

Figure 1 is a rear elevation of a wall embodying the invention. Figs. 2 and 3 are enlarged sections on the lines II-II and III-III, respectively, of Fig. 1. Fig. 4 is an enlarged detail elevation. Fig. 5 comprises front and end views of one of the locking keys. Figs. 6 and 7 are fragmentary perspective views of the outside and inside of a wall embodying the improved construction as applied to the corner of a building. And Fig. 8 is an enlarged perspective view of one of the corner blocks.

Fig. 1 shows seven blocks in part or in whole, all similar and designated by the letters A, B, C, D, E, F, G, the block D being the only one which is completely shown. Each block is reinforced by the three transverse metal bars 1, 1, 1, and at each vertical edge of the block is a groove in which is seated a metal angle 2 secured to the ends of the bars 1, 1, 1 by means of the rivets 3. Paralleling the inner flanges of the angle members 2 are the metal strips 4, also secured to the bars by the rivets 3, thus providing the spaces 5 (Fig. 3) for the reception of the keys 6 (Fig. 5), later described. The outer flanges of the angle members 2 project out past the inner faces of the concrete blocks and are adapted to secure the wood strips 7 (Figs. 1 and 7), which are secured in position by the nails or screws 8 extending through suitable perforations in the flanges. These wood strips are adapted to carry the lath or plasterboard, which constitutes the inner facing of the wall. They also assist in holding the blocks together and in alinement.

Other means are also provided for holding the blocks securely in abutting relation, such

means comprising the keys 6 and the screws 9 (Figs. 4 and 5). The keys are provided with the slots 10 adapted to straddle the screws 9, as indicated in Fig. 4, the screws 9 being similar to the rivets 3. After the key is positioned, as indicated in Fig. 4, in the spaces 5 between the strips 4 and the lower flanges of the angle members 2, which latter are cut away, as indicated at 6a, to permit the insertion of the key, the screws are screwed in, springing the flange of the angle member down so that it clamps the key against the strips 4. This securely holds the blocks against movement away from each other.

Each of the blocks is provided (in addition to the grooves at the edges carrying the angle members 2) with another groove 10 (Fig. 1). The purpose of these grooves is to permit the staggered arrangement of the blocks, shown in Figs. 1 and 7, without interfering with the use of the wood strips 7. For instance, the wood strip lying in the groove between the flanges of the angles 2, 2 at the meeting edges of the blocks D and E (Fig. 1), fits into the grooves 10, 10, in the blocks B and G lying above and below the blocks D and E. The use of continuous wood strips is thus provided for, and additional aligning and holding means are provided for the blocks despite their staggered arrangement. The staggered relation is regarded as desirable, because of the matter of appearance, and because of the greater strength of a wall having broken joints.

Fig. 6 shows the appearance of the wall at one of the corners of a building; blocks similar to the block 11 shown in detail in Fig. 8, being employed at the corners. The construction of this block follows that of the flat block aside from the wing employed at the corner. Similar angle members 2, 2 are employed at the edges, and the method of locking the angle members to other adjacent ones is the same as that shown in Figs. 4 and 5. For the sake of appearance the blocks may be varied in dimension, as indicated in Fig. 6, but for the most part, a block of standard size, preferably about 18 by 32 inches, is employed.

Fig. 7 shows a somewhat different corner arrangement, as special elongated blocks 12 are used in place of the wing blocks 11. These blocks are secured to the adjacent standard blocks A, as heretofore described by means of angle members 2 secured to the

edges of the blocks 12 in the same manner that they are secured to standard blocks. This figure also shows the method of applying the woodwork to the lower portion of the structure. The blocks are supported upon the foundation courses 13 and 14, provided with the ledge 15 for carrying the planks 16 and 17 and the ends of the joists 18, upon the latter of which the flooring 19 is placed. As indicated most clearly in Figs. 7 and 8, the upper and lower edges of the blocks are provided with the ribs 20 and grooves 21 to assist in aligning the blocks and holding them against relative in and out movement. The joints between the blocks are provided with the usual mastic cement containing a high percentage of asphalt.

The strips 7, or studs, as they are ordinarily called, are shown as wood, but other material might be used, as for instance, suitably bent sheet metal members, and the invention is not limited in this particular. The invention is further not limited to the use of wood lathing back of the studding, as metal lath may be used. It will also be apparent that the invention is not limited to making the angle members 2, 2 of the length shown, as they may be made in short lengths, or that it is limited to having such angle members separate from the reinforcing 1, 1, 1 and riveted thereto, rather than integral, although the arrangement shown is preferred because of its simplicity and cheapness.

35. What I claim is:

1. In combination, a wall consisting of concrete blocks placed edge to edge and having longitudinal recesses or rabbets at their meeting edges at the inner faces of the blocks, metal angle members seated in the grooves, metal reinforcing extending transversely through the blocks to which said angle members are secured, means attaching the inner flanges of the angle members directly together, studs lying between the flanges of the angle members and means attaching said studs to the angles.

2. In combination, a wall consisting of concrete blocks placed edge to edge and having longitudinal recesses or rabbets at their meeting edges at the inner faces of the blocks, metal angle members seated in the grooves, metal reinforcing extending transversely through the blocks to which said angle members are secured, means attaching the inner flanges of the angle members directly together, studs lying between the flanges of the angle members and means attaching said studs to the angles, said blocks being arranged in successive rows in staggered relation, and being provided with grooves intermediate their edges for receiving said studs.

3. In combination, a wall consisting of concrete blocks placed edge to edge and

having longitudinal recesses or rabbets at their meeting edges at the inner faces of the blocks, metal holding members carried by the blocks at the sides of said grooves, studs lying in said rabbets between said holding members, and means securing the studs to said members, said blocks being arranged in rows one above the other in staggered relation and being provided with grooves intermediate their edges for receiving said studs. 75

4. In combination in a wall consisting of reinforced concrete blocks placed edge to edge and having longitudinal recesses or rabbets at their meeting edges at the inner faces of the blocks, metal holding members at the sides of said grooves secured to the reinforcing of the blocks, wood studs lying in said rabbets between said holding members, and means securing the studs to said members, said blocks being arranged in 80 rows one above the other in staggered relation and being provided with grooves intermediate their edges for receiving said studs.

5. In combination, a wall consisting of concrete blocks placed edge to edge and having longitudinal recesses or rabbets at their meeting edges at the inner faces of the blocks, metal angle members seated in the grooves, metal reinforcing extending transversely through the blocks to which said angle members are secured, metal key members attaching the inner flanges of the angle members on opposing blocks together, studs lying between the outer flanges of the angle members, and means attaching the studs to 100 said outer flanges.

6. In combination, a wall consisting of concrete blocks placed edge to edge and having longitudinal recesses or rabbets at their meeting edges at the inner faces of the blocks, metal angle members seated in the grooves, metal reinforcing extending transversely through the blocks to which said angle members are secured, metal key members attaching the inner flanges of the angle members on opposing blocks together, wood studs lying between the outer flanges of the angle members, said outer flanges extending out past the faces of the blocks and being perforated for the passage of fastening 110 devices, and fastening devices extending through said perforations and into the studs.

7. In combination, a wall consisting of concrete blocks placed edge to edge and having longitudinal recesses or rabbets at 120 their meeting edges at the inner faces of the blocks, metal angle members seated in the grooves, metal reinforcing extending transversely through the blocks to which said angle members are secured, means attaching the inner flanges of opposing angle members together, studs lying between the outer flanges of said opposing angle members, said outer flanges extending out past the faces of the blocks and being per- 125 130

forated for the passage of fastening devices, and fastening devices extending through said perforations and into the studs.

8. In combination, a wall consisting of 5 concrete blocks placed edge to edge and having longitudinal recesses or rabbets at their meeting edges at the inner faces of the blocks, metal strips extending along the inner sides of the grooves, reinforcing members extending transversely of the blocks with their ends extending over said strips, metal angle members seated in the rabbets with their inner flanges lying over the ends of said reinforcing members, means securing 10 said inner flanges to the ends of said reinforcing members, metal key members securing the inner flanges of said angle members together, said key members lying in the space between the inner flanges of the angle 15 members and said metal strips lying therebeneath, and means clamping the key members in position.

9. In combination, a wall consisting of

concrete blocks placed edge to edge and grooved at the meeting edges, metal strips 25 extending along the inner sides of the grooves, reinforcing members extending transversely of the blocks with their ends extending over said strips, metal angle members seated in the rabbets with their inner flanges lying over the ends of said reinforcing members, means securing said inner flanges to the ends of said reinforcing member, metal key members securing the inner flanges of said angle members together, 30 said key members lying in the space between the inner flanges of the angle members and said metal strips lying therebeneath, and screw means for causing a movement of approach between said metal strips and the inner flanges of the angle members, to clamp 35 the key members in position.

In testimony whereof, I have hereunto subscribed my name this 27th day of August, 1926.

CHARLES D. McARTHUR.

CERTIFICATE OF CORRECTION.

Patent No. 1,617,535,

granted February 15, 1927.

to CHARLES D. McARTHUR.

It is hereby certified that error appears in the printed specification of the above mentioned patent requiring correction as follows: Page 2, lines 41, 53, 69, 81, 94, 107 and 123, claims 1 to 7 respectively, and page 3, line 9, claim 8, for the word "grooves" read "rabbets"; and that the said Letters Patent should be read with these corrections therein that the same may conform to the record of the case in the Patent Office.

Signed and sealed this 8th day of March, A. D. 1927.

Seal.

M. J. Moore,
Acting Commissioner of Patents.
